Primary Examiner — Philip S Hyder*Assistant Examiner* — Darlington Ly(74) *Attorney, Agent, or Firm* — Gordon Kessler**(57) CLAIM**

The ornamental design for a photographic light director, as shown and described.

DESCRIPTION

FIG. 1 is a perspective view of a photographic light director constructed in accordance with the invention;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view; and,

FIG. 8 is a second perspective view thereof.

The broken lines illustrate portions of the photographic light director and environmental matter that forms no part of the claimed design.

1 Claim, 8 Drawing Sheets(56)
